BOTTLE

Arnold I. Lorenzen, Toledo, Ohio, assignor to Owens-Illinois Glass Company, Toledo, Ohio, a corporation of Ohio

Filed Aug. 1, 1963, Ser. No. 76,063

Term of patent 14 years

(Cl. D58—6)

FIG. 1

The side and back not shown are the same as the side and front shown.

The dominant features of this design reside in the portion shown in full lines with particular reference to the groove circumscribing the elliptical portion on the front and back of the container, which groove extends into both sides of the container.

I claim:

The ornamental design for a bottle, substantially as shown and described.
